UNITED STATES PATENT OFFICE.

GOTTLIEB GRAESSLE, OF HAMILTON, OHIO.

DRAIN-TILE MACHINE.

Specification of Letters Patent No. 29,586, dated August 14, 1860.

To all whom it may concern:

Be it known that I, GOTTLIEB GRAESSLE, of Hamilton, Butler county, Ohio, have invented a certain new and useful Improvement 5 in Machines for Making Drain-Tiles; and I hereby declare the following to be a full, clear, and exact description of the same, reference being had to the accompanying drawings, making part of this specification.

10 In the accompanying drawings Figure 1 is an elevation of a machine embodying my improvement, a part of the "tempering tub" being in section. Fig. 2 is a sectional plan and Figs. 3 and 4 details.

15 A is the frame of the machine.

B is the tempering tub provided with vertical shaft G having attached tempering blades D and forcing screw blade E, these by a rotation in direction of arrow being 20 adapted to temper and force the clay through the apertures of gratings F F into the tubes or passages G G. These passages are arranged on opposite sides of the shaft C so as to give greater facility for cleaning 25 and repairing, and space for the construction of air vents. The ends of passages G are fitted with mold boards g of a shape corresponding to that required to be given to the tiles. The same or different shapes of 30 tiles can be produced from the tubes G at the same time. If necessary one tube only may be worked at a time by placing a plate over one of the grates F. The grates F are attached to slides H and may be changed 35 when desirable. I I' is a sliding frame fitted with suitable anti-friction rollers a a.

It is provided with side plates K extending into and fitted to slide snugly in tubes G. A reciprocating sliding motion is given to this frame by means of a rollered lever J 40 secured to shaft C. The sides I' pass backward and forward across the gratings F, by the action of which the clay is received from tub B and delivered at molds g. The sides I' have air vents b b fitted with suitable 45 valves to admit air to tubes G on the return stroke of sides, I'.

To prevent the clay from adhering to the molds I construct them of wood boiled in oil, in preference to metal or other material. 50 The interior portion g' is connected to the exterior portion g by means of a bridge L extending backward in the manner exhibited so that a tubular tile of any desired form may be delivered from the mold without 55 seam.

I claim as new and of my invention herein as an improvement in drain tile machines—

1. The oil boiled wooden molds g g' constructed and applied in the manner and for 60 the purpose set forth.

2. The combination and arrangement of the tempering tub B C D E, grated slides F H sliding frame I I' valves b and molding tubes G, constructed and operating in the 65 manner and for the purposes set forth.

In testimony of which invention, I hereunto set my hand.

GOTTLIEB GRAESSLE.
